UNITED STATES PATENT OFFICE.

DELIA GOODALE, OF FORT COLLINS, COLORADO.

DESIGN FOR A SERVICE-TRAY.

57,968.

Specification for Design. Patented May 24, 1921.

Application filed October 2, 1920. Serial No. 414,375. Term of patent 7 years.

To all whom it may concern:

Be it known that I, DELIA GOODALE, a citizen of the United States, residing at Fort Collins, in the county of Larimer and State of Colorado, have invented a new, original, and ornamental Design for a Service-Tray, of which the following is a specification.

Referring to the drawing:

Figure 1 is a perspective view of a service tray showing my new design; and

Fig. 2 is a bottom plan view of the same.

I claim:—

The ornamental design for a service tray, substantially as shown.

In testimony that I claim the foregoing as my own I have hereto affixed my signature.

DELIA GOODALE.
